G. H. CURTISS.
FOLDING WING AIRPLANE.
APPLICATION FILED NOV. 8, 1918.

1,316,280.

Patented Sept. 16, 1919.

FIG.1.

FIG.2.

Inventor
GLENN H. CURTISS

By his Attorney

John P. Lombard

UNITED STATES PATENT OFFICE.

GLENN H. CURTISS, OF GARDEN CITY, NEW YORK, ASSIGNOR TO CURTISS ENGINEERING CORPORATION, OF GARDEN CITY, NEW YORK, A CORPORATION OF NEW YORK.

FOLDING-WING AIRPLANE.

1,316,280.

Specification of Letters Patent. Patented Sept. 16, 1919.

Application filed November 8, 1918. Serial No. 261,594.

To all whom it may concern:

Be it known that I, GLENN H. CURTISS, a citizen of the United States, residing at Garden City, in the county of Nassau and State 5 of New York, have invented certain new and useful Improvements in Folding-Wing Airplanes, of which the following is a specification.

My invention relates to airplanes and more 10 particularly to airplanes of the folding wing type.

Airplanes of the folding wing type are broadly old. Patent No. 1,223,317 issued to me April 7th, 1917, may be cited by way of 15 example. This patent, like a number of other patents, discloses the idea of folding wings backwardly substantially in the plane of the fuselage or body. Such an arrangement, while advantageous from one point 20 of view, is more or less objectionable in that interference between either the wings or the ailerons and the empennage of the craft is bound to exist. This interference is especially objectionable where the ailerons, 25 mounted at the wing tips, are of the trailing edge type, *i. e.*, a type in which the ailerons continue the wings rearwardly to an edge. For this reason more than any other, the vast majority of airplanes now in use are 30 provided with fixed or non-foldable wings.

The machine of the present invention unlike existing machines, is provided with wings which fold forwardly. Such an arrangement is of particular applicability to 35 small machines wherein the stagger of the wings and the size of the tail surfaces (empennage) and their proximity to the wings is such that the wings cannot be folded back close to the body without interference be- 40 tween it (the body) and either the ailerons or the wings. When forwardly folded, the ailerons, carried by the wings, will extend outwardly or away from the body rather than inwardly and toward it as heretofore.

Moreover, the relative arrangement of the 45 wing posts and the span or spread of both the tail surfaces and the supporting surfaces as well as the distance between the supporting surfaces and the tail surfaces are 50 immaterial. When folded forwardly the arrangement of the wings is such that the empennage occupies a position remote from the wings while the propeller or propellers (assuming that the machine is of the tractor 55 type) occupy the space between the folded

wings. The wings, when folded, should preferably occupy positions substantially parallel with the fore and aft axis of the craft. Other advantages will be hereinafter disclosed. The invention *per se*, however, 60 is pointed out in the claims.

Of the drawings, wherein like characters of reference designate like or corresponding parts,

Figure 1 is a side elevation of a biplane 65 airplane, the dotted lines indicating the positions which the wings occupy when folded, and

Fig. 2 is a top plan view of the machine illustrated in Fig. 1, the dotted lines again 70 indicating the folded position of the wings.

A folding wing airplane is advantageous in that it may be housed in a very small space when not used, may be rendered ready for use quickly and with little trouble, and 75 when in use may be, upon landing, rendered almost instantly storm proof by the substantial reduction in the lifting efficiency of its wings. If used in connection with a hydro machine, the wings may be folded and the 80 machine operated as a water craft or hydroplane. The big advantage, however, is the relative compactness of the machine when not in use.

In the selected embodiment of the invention 85 a biplane airplane is disclosed. The invention, however, is applicable to any and all types of machines, both land and water, and regardless of whether the machine is of the pusher or tractor type. In the machine 90 disclosed, however, the fuselage or body is designated as 10, the supporting surfaces as 11-11, the landing gear as 12, the empennage as 13 and the power plant as 14. The supporting surfaces 11-11 are prefer- 95 ably of the panel type and include outer panels 14' and engine section panels 15, only the outer panels 14' being foldable as hereinafter pointed out. The empennage 13 comprises the usual vertical stabilizer 16, 100 vertical rudder 17, horizontal stabilizer 18 and elevator flaps 19. The power plant includes in addition to the motor (preferably inclosed in the body of the craft) a propeller 20 of the tractor type.

The outer panels 14' of the supporting surfaces are hingedly connected as at 21 and 22 to the engine section panels 15, prefer- 105 ably in the plane of the wing beams (not shown) of the wings. The hinges 21, *i. e.*, 110

the rear hinges are preferably of a construction such that the connection between the outer panels and the engine section panels may be quickly broken and the panels 14 5 folded forwardly about the hinges 22. The construction of the hinges 22 is such that the axes about which the wings fold forwardly extend substantially vertically so that the wings, when folded, will occupy 10 positions at opposite sides of the fore and aft axis of the machine preferably parallel therewith.

By folding the wings or panels 14' forwardly rather than backwardly as heretofore, all possibility of interference between 15 the wings and the tail surfaces is avoided. This arrangement, while applicable to all types of machines, is especially applicable to scout machines wherein the distance between 20 the wings and the empennage is small. The wings, when folded, occupy positions at opposite sides of the propeller 20 and the latter, to avoid interference with the wings, should occupy a vertical or substantially 25 vertical position.

As indicated hereinbefore, much trouble has been encountered in designing folding wing airplanes to avoid interference between the ailerons of the machine and the 30 empennage when the wings are folded back. It is either necessary to dispense with the trailing edge type of aileron (which are decidedly the best) or so relate the wings to the body of the machine as to enable the 35 former to be folded backward without interference. Indeed, if the wings are staggered, as they are in many instances, a backward folding of the wings into positions in close proximity to the sides of the fuselage is 40 next to impossible. The stagger or angular relation of the wings is such that one of the wings interferes. On the other hand, by folding the wings forwardly all possibility of interference is avoided. Ailerons of the 45 desired trailing edge type may be used for the ailerons herein designated as 23 will occupy positions, when the wings are folded, remote from the empennage rather than in close proximity thereto as heretofore. The 50 relative arrangement of the ailerons with respect to the fuselage or body, when the wings are folded, is brought out in Fig. 2. Furthermore, the wings, when folded forwardly, offer a protection for the propeller 55 which, as is well known, if exposed upon all sides, is often accidentally broken or mutilated due to extraneous cause.

Still another important advantage in folding the wings forwardly rather than backwardly is that no consideration need be 60 given the span or spread of the wings or

the relative arrangement of the wing posts other than such considerations as are given in the design of a machine having non-foldable wings. The empennage may be located 65 as desired for it is not necessary that the distance between the wings and the empennage be greater than the span of the wings. These advantages, together with the advantages above pointed out, render the folding wing airplane in which the wings are forwardly folded a big improvement over 70 existing types wherein the wings are foldable backwardly.

While I have described my invention in 75 detail in its present preferred embodiment, it will be obvious to those skilled in the art after understanding my invention, that various changes and modifications may be made therein without departing from the 80 spirit or scope thereof. I aim in the appended claims to cover all such modifications and changes.

What is claimed is:

1. In an aeroplane, the combination of a 85 fuselage, an empennage, and forwardly foldable wings extended laterally out from the fuselage at points nearer its forward end than its rear end, the arrangement of the wings when folded, being such that they 90 (the wings) extend forwardly beyond the nose end of the fuselage to occupy positions remote from the empennage.

2. In an airplane, the combination of a fuselage, an empennage carried by the fuselage, 95 a propelling power plant including a tractor propeller, and forwardly foldable wings extended laterally out from the fuselage, the arrangement of the wings, when folded, being such that the empennage occupies a 100 position remote therefrom while the propeller occupies the space between the folded wings.

3. In an airplane, the combination of a fuselage, an empennage carried by the fuselage, 105 forwardly foldable wings extended laterally out from the fuselage, trailing edge ailerons mounted at or near the wing tips, the relative arrangement of the ailerons and empennage, when the wings are folded, 110 being such that the empennage occupies a position remote therefrom.

4. In an aeroplane, the combination of a fuselage, a propelling power plant including a tractor propeller, and forwardly foldable 115 wings extend laterally out from the fuselage, the arrangement of the wings, when folded, being such that the propeller occupies the space between the folded wings.

In testimony whereof I hereunto affix my 120 signature.

GLENN H. CURTISS.
